UNITED STATES PATENT OFFICE.

EUGENE MACON COLE, OF CHARLOTTE, NORTH CAROLINA.

FERTILIZER-DISTRIBUTER.

1,074,929.

Specification of Letters Patent.

Patented Oct. 7, 1913.

Application filed June 14, 1911. Serial No. 633,093.

To all whom it may concern:

Be it known that I, EUGENE M. COLE, a citizen of the United States, residing at Charlotte, in the county of Mecklenburg 5 and State of North Carolina, have invented a new and useful Fertilizer-Distributer, of which the following is a specification.

This invention relates to an improvement in fertilizer distributers.

10 The primary object of said invention is to provide a distributing device which while intended to distribute guano or other fertilizer will be equally adapted to distribute seed.

15 In the drawings:—Figure 1 is a side elevation of the machine. Fig. 2 is a top plan view. Fig. 3 is a section transversely through the distributing mechanism on line 3—3 Fig. 2, the scraper being removed. Fig. 4 is a detail 20 view showing the manner of supporting the feed screw by means of which the material is fed to the top of the hopper. Fig. 5 is a top plan view of said screw supporting structure. Fig. 6 is a perspective of one of 25 the jaws employed in supporting said feed screw, and Fig. 7 is a perspective view of the device which when the set screw has reached a certain height will operate to prevent the further rotation of the same.

30 In the drawings, 10 and 11 designate the side beams of the distributer frame, each of said beams being provided with suitable covering devices 12. Supported at a point adjacent the forward end of said beams are the 35 handles 13 and 14 which are of the usual construction. The beams are connected at their forward ends by a block 15 which supports a suitable clevis 16. Rotatably supported between the beams adjacent their 40 forward ends is a drive wheel 17, said wheel being supported on a shaft or axle 16' the ends of which extend within bearings 18 which are formed integral with and extend at right angles to brackets 19 bolted or otherwise 45 secured to the beams and to which the handles are secured. Arranged on said shaft is a gear 20 and secured to the beams above and to the rear of said gear is a supporting plate 21, said plate 21 being provided with an enlarged extended end portion 22 which is formed with a slot 23 which 50 receives the supporting shaft 24 of a gear 25. This slot 23 is so disposed that large and small gears may be mounted on the 55 shaft 24, the interchanging of the gear in

this point of the transmission regulating the speed of the distributing mechanism. Supported by the plate 21 are a plurality of gears 22', 23' and 24' which transmit the movement of the drive wheel 17 to a gear 60 25', the shaft on which said gear is mounted being embraced by the slotted arms 26' which also support the shaft on which the gear 24' is mounted. Extending transversely between the beams 10 and 11 is a supporting member 27 and on which is arranged a block 28. This block supports a bracket 29 whose body portion 29' forms a bearing surface for a rotating hopper 30, secured to the end of which are one or more bowed supporting members 31. The central portions 65 of these members rest upon the portion 29' of the support 29, a bolt 28' passing through the portion 29' and the body portion of the member 31, and the hopper being free 70 to rotate on said bracket. The hopper is cylindrical and is held against lateral movement by the semi-circular support 32 which partially embraces the same, the end portions of the support 32 being secured to uprights 33 which are supported by the beams and which intersect and are secured to the handles 13 and 14, at the point 33'. These uprights 33 extend beyond the semi-circular support 32 to a point above the cylinder, 75 the uprights terminating centrally of the cylinder and being connected by the spaced supporting members 34. Arranged within the hopper is a circular plate 35, which forms the bottom of the hopper. Secured 80 centrally to said plate is a feed screw 36 which is screw threaded its entire length and which extends between the members 34. Pivottally supported by the members 34 are the screw threaded jaws 37, said jaws 85 being pivoted adjacent their lower ends, and provided with the interiorly arranged threads 39, which when the jaws are in their normal position receive the feed screw 36 advancing the same, as the screw is rotated. 90

Arranged on the bottom of the hopper is a gear 40 which meshes with the pivotally supported gear 25', the rotation imparted to said gear 25' by means of the drive wheel 17 thus rotating the hopper. A vertically 105 extended rib 41 is secured to the inner wall of the hopper, said rib or key extending within a key-way formed in the circular plate or bottom 35, thus as the cylinder or hopper is rotated by means of the pinion 110

25', the rotation will be transmitted to the bottom of the hopper by means of the rib 41, thus the feed screw will be rotated, and by the arrangement of the screw threaded 5 jaw members the bottom will be advanced, feeding the material upward. Secured to one of the members 34, is a stationary scraper 43. As the hopper is rotated and the material fed upward by means of the 10 vertically movable bottom 35, this scraper deflects the guano or seed into a vertically disposed spout 44 which extends parallel with the hopper and which empties into a second spout 45 which deposits the same on 15 the ground. It will be seen that by this arrangement that an even distribution of the seed or fertilizer is secured.

The gear 25' which is in mesh with the gear 40 arranged on the bottom of the hopper 20 per is pivotally supported by the arms 26' which are supported by the shaft on which the gear 24 is mounted. The shaft on which the gear 25' is mounted is pivotally supported by the arm 46' of a bell crank 46, 25 said crank being connected with an operating rod 47 which passes through a bracket 48 which is secured to one of the beams, a coiled spring 48' being interposed between the end portions of the lever 46 and said 30 bracket in order to normally hold the gear in mesh with the gear which drives the hopper. It will be noted that by operating the rod 47 to compress the spring 48' the bell crank lever will be swung on its pivot and 35 the gear 24' thrown out of mesh with the gear 25' which drives the hopper. Thus the machine may be propelled without operating the distributing mechanism. It will also be noted that the gear 25 is normally 40 in mesh with the gear arranged on the drive shaft. Its peculiar mounting however permits said gear to be thrown out of mesh with the first mentioned gear as soon as the movement of the drive wheel is reversed, so 45 that in backing the machine the distributing mechanism will not be operated.

In order to prevent the rotation of the bottom 35 after the same has reached a certain height, a yoke 49 is employed, said yoke 50 embracing the jaw members between which the feed screw extends. This yoke is formed with a pair of downwardly extending arms 49' and the inwardly extending projections 50, of the yoke being so positioned that said 55 projections lie between the jaws. The arms 49' straddle the members 34 and extend downwardly beyond said members, extending parallel with the feed screw. It will be noted that as the bottom 35 is advanced to 60 a point adjacent the top of the hopper, the upper jam nut 36' which holds the feed screw in contact with the bottom 35 will contact with said arms, forcing the yoke upward causing the inwardly extending 65 projections 50 to contact with the beveled

portions 51 of the jaws to separate the same thus preventing the further advancing of the screw.

It will be noted that by increasing the thickness of the jam nut 36' or placing a 70 sleeve on said nut, that the operation of the jaw opening yoke may be accurately timed, the feeding of the screw discontinued as soon as said sleeve or projection contacts with the downwardly extending arms 49', 75 thus by placing a long sleeve on the feed screw 36 the threaded jam nuts will be separated and consequently the advancing of the bottom 35 will be stopped before said bottom can reach a point adjacent the top 80 of the hopper, the opening of the jaws permitting the rotation of the bottom 35 yet preventing its upward advancement.

It will be noted from the foregoing that the distribution of the seed or fertilizer may 85 be regulated in proportion to the ground covered by interchanging the gears arranged between the bottom of the hopper and the main drive gear positioned on the shaft 16', as by a proper arrangement of the gears, 90 the speed of the hopper, and consequently the speed of the distributing mechanism, is increased or diminished. Thus the machine may travel at a comparatively low rate of speed and the distributing mechanism be 95 geared to travel at a high rate of speed, or the gearing may be such as to permit the rapid travel of the machine and at the same time actuate the distributing mechanism so that the same will operate slowly. In this 100 manner the distribution of the fertilizer is accurately determined and its distribution arranged accordingly to suit varying conditions.

It will be noted that the invention is not 105 confined to the structure shown, as a plurality of the scraper members 43 and a plurality of spouts 44 may be employed, various changes being permissible in the gearing in order to drive the hopper.

What is claimed is:—

1. In a fertilizer distributer, a receptacle mounted for rotation, a bottom member adapted to slide within and to rotate with the receptacle, a feed screw movable with 115 said bottom, means engaged by the screw during its rotation in the receptacle for shifting the screw and the bottom vertically, and a stationary spacing element extending over the receptacle. 120

2. In a fertilizer distributer, a receptacle mounted for rotation, a bottom member adapted to slide within and to rotate with the receptacle, a feed screw movable with 125 said bottom, means engaged by the screw during its rotation in the receptacle for shifting the screw and the bottom vertically, a stationary spout extending downwardly from the upper end of and adjacent the receptacle, and a stationary scraper above the 130

receptacle for directing material into the spout.

3. In a fertilizer distributer, a rotary hopper, a bottom arranged within said hopper, 5 said bottom being capable of a rotary and a vertical movement, means carried by said hopper for imparting rotary movement to said bottom, means for imparting a vertical movement to said bottom and means actuated by said bottom when at the limit of its movement in one direction to discontinue its vertical movement.

4. In a fertilizer distributer, a rotary hopper, a bottom arranged within said hopper, 15 said bottom being capable of a rotary and a vertical movement, means carried by said hopper for imparting rotary movement to said bottom, means for imparting a vertical movement to said bottom and relatively 20 movable means actuated by said bottom when at the limit of its upward movement to discontinue its vertical movement.

5. In a fertilizer distributer, a rotary hopper, a bottom arranged within said hopper, 25 a feed screw secured to said bottom, a key arranged interiorly of said hopper, said bottom being formed with a key-way arranged to register with said key, means for imparting rotary movement to said hopper, to rotate and vertically advance said bottom and 30 a plurality of pivotally supported interiorly screw threaded jaws embracing said screw.

6. In a fertilizer distributer, rotary hopper, a bottom arranged within said hopper, 35 a feed screw secured to said bottom, a key arranged interiorly of said hopper, said bottom being formed with a key-way arranged to register with said key, means for imparting rotary movement to said hopper, to rotate and vertically advance said bottom and 40 a plurality of pivotally supported interiorly screw threaded jaws embracing said screw and means actuated by the upward movement of said bottom to move said jaws on 45 their pivots.

7. In a fertilizer distributer, a rotary hopper, a bottom arranged within said hopper, means actuated by the hopper for imparting a rotary movement to said bottom, a feed 50 screw secured to the bottom, a plurality of

screw threaded jaws embracing said feed screw and means carried by said bottom for releasing said jaws from said screw.

8. In a fertilizer distributer, a rotary hopper, a drive wheel, gears rotated by the 55 shaft on which said drive wheel is mounted, one of said gears being pivotally supported, a gear in mesh with said pivotally supported gear, said gear being capable of imparting a rotary movement to said hopper, a 60 bottom arranged within said hopper, said bottom being capable of a rotary and vertical movement, a bracket arranged above said hopper, a stationary distributer supported by said bracket and a receiving spout arranged adjacent said distributer.

9. In a fertilizer distributer, a rotary hopper, a bottom arranged within said hopper, means for imparting a rotary and vertical movement to said bottom, a bracket above 70 said hopper, a screw secured to said bottom, a plurality of screw threaded jaws pivotally supported by said bracket, a yoke embracing said jaws, said yoke being formed with downwardly extending arms arranged 75 in the path of movement of said bottom, and a plurality of inwardly extending arms formed integral with said yoke, said arms contacting with said pivoted jaws to separate the same when said downwardly extending arms contact with said bottom.

10. In a fertilizer distributer, a hopper, a bottom arranged within the hopper, a feed screw connected to the bottom, means for rotating the feed screw, a threaded member 85 engaged by the feed screw for shifting the screw and bottom vertically during the rotation of the screw, and means operated by the bottom when brought to a predetermined elevation for actuating said member to release the screw therefrom and stop the vertical movement thereof.

In testimony that I claim the foregoing as my own, I have hereto affixed my signature in the presence of two witnesses.

EUGENE MACON COLE.
